UNITED STATES PATENT OFFICE
CONCRETE FORM SPACER
Roy C. Day, Crawfordsville, Ind.
Application June 27, 1938, Serial No. 316,026
2 Claims. (Cl. 25—131)

My invention relates to improvements in concrete form spacers and it more especially includes the features pointed out in the claims.

The purpose of my invention is to provide means for expeditiously adjusting the co-related sides of concrete forms into alignment; that uses a central rod which passes through the form on which rapidly adjustable clamps are positioned on the outsides of the form walls; that provides means for retaining such rods within the completed concrete against endwise movement and against turning while the ends are cut off some distance in from the finished outer faces after which the openings left by the cones can be sealed off by placing cement around the rods to close the opening left by the positioning cones, against leakage through the concrete walls.

This invention is an improvement on that disclosed in my Patent No. 2,069,085 of January 26, 1937.

With these and other ends in view I illustrate in the accompanying drawing such instances of adaptation as will disclose the broad features of my invention without limiting myself to the specific details shown thereon and described herein.

Fig. 1 is a side elevation partly in section showing spacing collars applied to the tie rod on which the adjusting clamps are attached outside of the form.

Fig. 2 is a detached elevation of a positioning collar and an adjacent elevation.

Fig. 3 is a detached sectional view showing the closing of the cone cavities.

Fig. 4 is an end elevation of a clamping barrel and wedge.

Fig. 5 is a modification of Fig. 1 in that an additional adjusting clamp is shown to supplement the clamping devices shown in Fig. 1 and in my Patent No. 2,069,085.

Fig. 6 is an end view of a modified clamp and wedge.

Fig. 7 is a plan view of the modified clamp.

Fig. 8 is a side elevation of Fig. 7.

In using my invention I may employ whatever alternatives, or equivalents of structure that the exigencies of varying conditions may demand without departing from the underlying broad spirit of the invention.

In the drawing a conventional type of concrete form is shown. It comprises the usual board sides 1 secured to studdings 2. Wherever it is desired to hold the sides of the form in a definite spaced apart relation, liners or walers 3 are nailed to the studding so as to form an abutment for the end clamps 4. Holes are usually 55

55 drilled in the walers 3 and the studdings 2. The form is held in position by the clamps 4 which are secured to the walers 3 and the studdings 2. The clamps 4 are secured to the walers 3 by means of a wedge 6 which is driven into the hole 55. The wedge 6 is held in the hole 55 by reason of the fact that the hole 55 is formed lengthwise in the wedge 6.

Fig. 1 shows the form 1 in position with the clamps 4 secured to the walers 3 and the studdings 2.

Fig. 2 shows the collar 11 and the cone 7 which is secured to the tie rod 5.

Fig. 3 shows the cone 7 being closed to close the opening left by the cone 7.

Fig. 4 shows the barrel 17 and the wedge 6.

Fig. 5 shows the form 1 in position with the clamps 4 secured to the walers 3 and the studdings 2.

Fig. 6 shows the collar 11 and the cone 7 which is secured to the tie rod 5. The tie rod 5 passes through the boards 1 on one side in alignment with similar holes made in the boards on the other side of the form. Clamp holding tie rods 5 pass through these holes and they project a suitable distance outside of each clamp 4. At the left-hand end of Fig. 1, a clamp 4 provided with a wedge take-up 6 is positioned on the rod 5. This clamp has an enlarged diameter bearing end that engages the walers 3. On the inside of the form 1, a cone 7 is positioned on a tubular end adjustment 8 that is threaded in the cone. This tube outside of the form 1 is provided with a square or hexagon head 9 by means of which it is adjusted inside of the cone 7. This tube at the other end engages the small diameter 10 of a collar 11 that is secured to the tie rod 5 by a set screw 12.

At the right hand end of Fig. 1, a clamp 4 similar to that shown at the left hand side is positioned on the rod 5. On the inside of this wall of the form, a plain cone 13 is used associated with a collar 11 that is also fastened to the rod 5 by a set screw 12.

The side walls 1 of the form are brought into alignment by the adjusting clamps 4 on the outside of the form and the separate adjusting tube 8 which enters the cone 7.

In advance of pouring the concrete the side walls 1 of the form are brought into approximate alignment by the tube 8. Any further adjustment that is required may be made by the end clamps 4 of which the clamping lever 14 by reason of its teeth engaging the tie rod 5, is held firmly against end-wise movement. All the end clamps 4 as stated, have toothed levers 14 that are normally held in engagement with the rod 5 by light springs 15 placed between an extension 16 of the lever and an outside barrel 17. This barrel has an enlarged conical end 18 that rests against the walers 3. The barrel 17 is a support for an interiorly positioned tube 19 that may slide lengthwise of the barrel. The tube 19 is held against dropping out of the barrel 17 by a side screw 20 threaded into the tube 19. It passes through a slot 21 in the barrel. The barrel is slotted vertically to receive a bifurcated wedge 6 between the tube 19 and the enlarged inner end 18 of the barrel so as to finally draw the cone 7 tightly against the inner face of one of the sides 1 of the form.

After the concrete has set, the clamps 4 are removed and the form is taken down. The cones 7 and 13 are withdrawn and the small diameters 10 of the collars 11 are expanded by reason of slots 22 which are formed lengthwise in it, par-

allel to the axis of the collars. By suitable co-operating means the rod 5 at each end is cut off so as to terminate a desired distance inside of the face of the concrete. The rods 5 during this cutting off operation are securely held against turning in the concrete by reason of the set screws 12 on the collars 11. After the rods 5 are cut off the open space left by the withdrawn cones is filled in with cement.

In Fig. 5 at the left hand edge the same clamp 4 and an unthreaded cone 13 associated with the collar 11 is used. At the right hand edge of this figure, a supplemental clamp 23 is used within the studding space in addition to the clamp 4 shown at the left hand edge of the figure. The clamp 23 arrangement is associated with a tube 24 that passes over the rod 5. It has a large end 25 that abuts the small end of a cone 13'. The tube 24 is notched on each side at 26 so as to leave a wall 31 between the notches a little larger than the diameter of the rod 5. The barrel portion of this clamp which surrounds one end of the tube 24 has a similar wall 30 and is similarly notched at 27 but the end walls of the two notches are not in vertical alignment with each other so that a bifurcated wedge 6 driven into the space between one face of the notch 27 in the barrel and the opposite face of the notch 26 in the tube 24 will after the clamp lever 28 has engaged the rod 5, draw the cone 13 and the adjacent wall of the form outward to align it. The clamping lever 28 is also controlled by a spring 15 similar to the clamping lever 14 of a clamp 4. It has teeth 32 to engage the rod 5 that are eccentric to the pivot of the lever. At the upper end of the wedges 6 a chain may be secured and its other end secured to the barrel in any desired manner so that in use the wedges will not become lost.

When the concrete has set, the tube 24 and its cone 13 associated with the special clamp 23 are removed. After the form has been taken down, and the cone at the other end has also been removed the collar 11 in place on the rod 5 remains in the concrete, similar to the disposition of the cones 7 shown in Fig. 1.

In the use of my spacing clamps, etc., I may combine the regular clamps as shown in Fig. 1 or these clamps in combination with the special clamp shown in Fig. 5. In the latter event the two outside clamps position the tie rods in respect of the outside walls of the form, exterior of the studding. The clamp at the right hand

end of Fig. 5 is conventional, as described in my Patent No. 2,069,085. It secures an approximate first alignment which is completed by the special clamp.

5 The cones and the different clamps may be used in any other combinations than those shown, in other words I am not limited to the specific positions in which the parts are shown. The cones and tubes and barrels, etc., may be made of formed sheet metal as may be found desirable.

10 Self-aligning projections 29 are formed on the tube 24 to enter corresponding recesses in the barrel, Figs. 6 and 8. When the tube 24 is assembled in the barrel 23 these projections instantly align the uncut portions 30 of the barrel and the uncut portions 31 of the tube 24 for the reception of a wedge 6.

15 I may use my spacing clamps and tie rods without walers or studding for curb forms. The tie rods serve to properly space the forms to correct widths, which is of course done before the concrete is poured. The single tie rod serves an all around purpose, without the intervention of special spacing tubes, etc.

20 25 What I claim is:

1. A form clamp comprising a barrel, a spring-pressed toothed lever pivoted on the barrel, a pair of notches formed in the side walls of the barrel, a tube within the barrel having similar notches, a clamping rod within the tube adapted to be engaged by the toothed lever of the barrel, an enlarged end of the tube, a cone on the tube with its small end adjacent the large end of the tube, said cone being adapted to engage the adjacent wall of a form, and a bifurcated wedge adapted to pass through the notches formed in the tube and the barrel to thereby pull the cone against the form.

2. A form tie, comprising a one-piece unitary tie rod of desired length, a pair of tubes and attached external cones positioned on the rod near its ends, a toothed eccentric lever on each tube, a bifurcated wedge for each tube adapted to pass through a slot in the tube and straddle the rod as it is positioned in the tubes, a pair of internal cones on the rod, a collar on the rod adjacent the small end of one cone, a flanged tube on the rod the flange engaging the small end of the other cone, and means for positioning the several cones on the rod independently of each other.
